John W. Hammes

UNITED STATES PATENT OFFICE.

JOHN W. HAMMES, OF RACINE, WISCONSIN.

FLOATING WEATHER STRIP.

1,422,569.

Specification of Letters Patent. Patented July 11, 1922.

Application filed May 23, 1921. Serial No. 471,805.

To all whom it may concern:

Be it known that I, JOHN W. HAMMES, a citizen of the United States, and resident of Racine, in the county of Racine and State of Wisconsin, have invented certain new and useful Improvements in Floating Weather Strips; and I do hereby declare that the following is a full, clear, and exact description thereof.

- 10 My invention refers to weather strips for swinging doors, windows or the like, the primary object being to provide a simple, economical and positively acting weather strip of a yielding rolling type, whereby the 15 joint between the door or window and the frame is in effect hermetically sealed, and variations in the width of the gap to be sealed are automatically taken up, so as to materially increase the life of the strip.
- 20 With the above and other minor objects in view, the invention consists in certain 25 peculiarities of construction and combination of parts, as are hereinafter set forth with reference to the accompanying drawings and subsequently claimed.

In the drawings:

Figure 1 represents a side elevation of the bottom of a swinging door equipped with a rolling weather strip structure embodying the features of my invention.

Figure 2 is a cross section of the same, the section being indicated by line 2-2 of Figure 1.

Figure 3 is an end elevation of the door 35 showing a retainer plate employed in connection with my improved weather strip structure.

- 40 Referring by characters to the drawings, with especial reference to Figures 1 to 3, A represents the bottom portion of a door provided with a longitudinal cavity B. The end edges of the cavity are formed with upwardly extended narrow channels α which serve as pockets for parts of a retainer plate 45 1. Each retainer plate is secured to an end edge of the door, whereby the cavity and channel are closed. The plate is formed in this instance with an inturned apertured ear 2, for the reception of a guide plunger 3, which guide plunger is secured to a projection that is formed upon an apertured ear bracket 4. The ear bracket is arranged to slide upon the inner surface of the plate

1, and the aperture thereof forms a journal for the pintle 5 of a yieldable roller 6. 55 The roller may be formed with a central core which is jacketed by an outer cover or tube of rubber, or analogous material, as best shown in Figure 2 of the drawings, it being understood that the jacket can be 60 replaced when worn down from wear by a simple operation.

It is also understood that each of the plate members for retaining the roller are similarly arranged in connection with the 65 door.

Thus it will be seen that the roller may ride and fall upon the floor or opposed wall to compensate for any irregularities therein and said roller, due to its projection 70 slightly below the bottom of the door, forms a sealing element for the gap developed between the bottom edge of said door and the opposed fixed surface. In practice it has been found that while the engagement between the roller and floor line will seal the 75 gap at this point, there is a certain lateral play necessary, whereby a more or less minute gap will develop between the surface of the rod 6 and the inner walls of the 80 cavity B. Hence, in such cases air and dust will not be excluded as they are free to pass between the walls of the cavity and the peripheral edges of the roller.

In order to overcome this leakage, I provide 85 an auxiliary floating rod which is loosely fitted into the cavity and arranged to rest upon the upper surface of the roller. This rod may be in the form of a round roller, or polygonal in shape, and it extends 90 from end to end of the cavity, whereby the gap is sealed, due to the fact that when the roll turns in either direction, this floating auxiliary rod or roller will drop against one of the side walls of the cavity and thus 95 seal the gap which would otherwise be free to permit a current of air to travel up and about the main roller 6.

While I have shown and described two forms of my invention, which embody the 100 broad features, obviously I may vary these details of construction within the scope of the claim.

I claim:

In a swinging closure having a longitudinally disposed cavity in its edge, a yield-

able floating roller mounted in the cavity and adapted to engage an opposed fixed surface to seal the gap between the fixed surface and the movable closure the combination of an auxiliary strip associated with the floating roller for engagement with the inner walls of the cavity, whereby currents of air

tending to travel therethrough are checked.

In testimony that I claim the foregoing I have hereunto set my hand at Milwaukee, ¹⁰ in the county of Milwaukee and State of Wisconsin.

JOHN W. HAMMES.
